UNITED STATES PATENT OFFICE

2,097,525

REFRIGERATING APPARATUS

Harry B. Hull, Dayton, Ohio, assignor, by mesne assignments, to General Motors Corporation, a corporation of Delaware

Original application April 13, 1927, Serial No. 183,480. Divided and this application January 18, 1932, Serial No. 587,301

3 Claims. (Cl. 74—242.15)

This application is a division of my copending application for Refrigerating apparatus, S. N. 183,480, filed April 13, 1927.

5 An object of this invention is to provide a refrigerator in which the machinery does not transmit vibrations and noises to the cabinet of the refrigerator.

Another object of this invention is to provide a mounting for an electric motor which mounting 10 is adapted to absorb the usual motor hum.

Another object of this invention is to provide an electrically driven refrigerator in which the motor is isolated from the rest of the machinery by rubber or other sound-deadening means.

15 Another object of this invention is to provide a mounting for a motor-driven compressor, which mounting is adapted to absorb the vibrations of the compressor and the hum of the motor.

20 A further object of the invention is to provide an improved adjustable mounting for maintaining taut the driving means between the motor and the compressor.

Further objects and advantages of the present invention will be apparent from the following 25 description, reference being had to the accompanying drawings, wherein a preferred form of the present invention is clearly shown.

In the drawings:

Fig. 1 is a front view of the refrigerating apparatus together with a longitudinal sectional view of the upper part of the refrigerator cabinet;

Fig. 2 is a view partly in section looking toward the refrigerating apparatus from the rear, and

Fig. 3 is a sectional view on a larger scale taken 35 on line 3—3 of Fig. 1.

Referring to the drawings, there is shown a cabinet 20 of a box-like structure comprising a refrigerating compartment 21 and a machine compartment 22. These compartments are separated from one another by a wall 23. A cooling unit 24 is carried by and below the wall 23 and extends within the refrigerating compartment 21, and a compressor 25, driving motor 26, and condenser 27 are carried by and on the top of said 40 wall 23. A fan (not shown) carried by the motor shaft is adapted to circulate air through the machine compartment 22 for cooling the condenser, the compressor, and the motor. A thermostat (not shown) is connected to the rear 45 of the cooling unit 24 and is operatively connected with a switch (not shown) for starting and stopping the driving motor 26 in response to the temperature of the cooling unit 24 and compartment 21.

55 The refrigerating apparatus for cooling the

compartment 21 is constructed as a subassembly which can be attached to and removed from the structure 20 as a unit. This assembly or unitary structure includes the partition wall 23, comprising a front rail 71, a rear rail (not shown) and side rails 73 and 74. A frame comprising the front rail 76, a rear rail (not shown) and side rails 78 and 79 are carried respectively below rails 71, 73, and 74. These frames constitute the removable base of the machine compartment 22. 10 Insulating material such as cork-board 80 is carried within these frames. A sheet metal plate 82 is secured on the under side of rails 76 and 79. This plate forms the top wall of the compartment 21 and is utilized to assist in maintaining 15 the cork-board 80 in position. Rails 73 and 74 rest respectively on rails 42 and 43, there being strips of soft insulating material such as a felt gasket 83 disposed between said rails to seal the joint.

20 The compressor 25 and the motor 26 are carried by a base 85. This base includes parallel extending angle irons 86 and 87 which are connected by cross bars or strips 88 and 89. A motor base plate 94 is suitably secured to angle irons 86 25 and 87 by bolts 95. This motor mounting includes rubber bushings 96 which receive a rod 97. A U-shaped bracket 98 is carried by the rod 97 and supports the motor 26 and the bushings 96 are maintained in position by retainers 99 which are 30 secured to the plate 94. By virtue of this construction the rod 97 and likewise the motor 26 pivot about the bushings 96.

35 The compressor herein shown is substantially the same as that shown in my copending application, Serial No. 179,955, filed March 31, 1927, now Patent 1,789,978. The crankcase 100 of the compressor 25 is provided with outwardly extending lugs 101 by which it is secured to the angle irons 86 and 87. These lugs are disposed adjacent the 40 crankshaft 103 of the compressor so as to minimize vibration. The rear end of the motor 26 carries the fan (not shown) and a pulley 105 and the rear end of the compressor 25 carries a pulley 104; these pulleys are connected with a belt 106. 45 A portion of the cork 80 and the rail 73 are cut away to provide clearance for the flywheel 104. One end of a brace 102 is secured to the crankcase of the compressor by a compressor mounting bolt and the other end thereof extends 50 within a bushing of shock absorbing material such as rubber 107a. This bushing is carried by a bracket 107 which is secured to the motor 26. Nuts 107b on the threaded brace 102 and on opposite sides of the bushing 107 provide means for 55

positioning the motor to adjust the belt tension and hold said motor in the adjusted position. The rubber bushing 107 absorbs vibrations and thereby prevents transmission of vibration from the motor to the base 85.

- 6 The base 85 and the apparatus carried thereby, including the motor and compressor, are suspended from a floating support at the center of oscillation of such apparatus. This support includes a metal plate 108 which is secured to rails 71 and 72. A bracket 109 is secured to the plate by rivets 110. This bracket extends upwardly and is provided with outwardly extending arms 111 and 112. Springs 113 and 114 depend, respectively, from the arms 111 and 112 and the spring 113 is connected with the angle iron 86 by a short strip 116, while the spring 114 is connected with an ear 117 secured to the angle iron 87 by an adjustable bolt 115.
- 10 For steadyng the base 85 and for preventing excessive oscillation thereof, the base 85 is provided at one end with the springs 121 which connect the base 85 with the side frame 13 and is provided at the other end with the springs 125 which connect the other end of the base 85 with the side frame 14.
- 15
- 20
- 25

While the form of embodiment of the invention as herein disclosed constitutes a preferred form, it is to be understood that other forms might be adopted, all coming within the scope of the claims which follow.

What is claimed is as follows:

1. In combination, a base, a driving device and a driven device mounted upon the base, one of said devices being pivotally mounted, pulley and belt driving means connecting the driving and the driven device, said pivotal mounting having its axis parallel to the axis of rotation of one of the pulleys of the pulley and belt driving means and a brace extending from the base to said pivotally mounted device for holding said pivotally mounted device in a position in which said belt driving means is maintained taut, said brace including a substantially straight rod, a bushing of rubber-

- 35
- 40

like material threaded upon the rod, nuts threaded on the rod located on the opposite sides of the rubber-like bushing for holding the bushing in place upon the rod, and means extending from the pivotally mounted device for gripping the outer surface of the bushing.

2. In combination, a horizontal base, a driving device and a driven device mounted upon and above the base, one of said devices being provided with rockable mounting between it and the base, 10 pulley and belt driving means connecting the driving and the driven devices, said one device being rockable upon the rockable mounting about an axis parallel to the axis of rotation of one of the pulleys of the pulley and belt driving means 15 and a brace connected at one end to the base and extending to a portion above the rockable mounting of said rockably mounted device for holding said device in a position to maintain the belt driving means taut, said brace being a substantially straight member, and a resilient adjustable connection connecting said brace and said rockably mounted device.

3. In combination, a horizontal base, a driving device and a driven device mounted upon and above said base, one of said devices being provided with a rockable mounting between it and the base, said rockable mounting being provided with vibration absorbing and sound deadening means, pulley and belt driving means connecting the driving and the driven devices, said rockably mounted device being rockable upon an axis parallel to the axis of rotation of one of the pulleys of the pulley and belt means, and a brace incorporating sound deadening and vibration absorbing means connected at one end to the base and extending diagonally between said devices, said brace being substantially straight and having an adjustable connection connected to a portion above the rockable mounting of said rockably 4 mounted device for holding said device in a position to maintain the belt driving means taut.

HARRY B. HULL.
